UNITED STATES PATENT OFFICE.

MAURICE H. GRAHAM, OF ST. LOUIS PARK, MINNESOTA.

DOOR OPERATING AND HOLDING MECHANISM.

Application filed February 14, 1927. Serial No. 167,990.

My invention has for its object to provide an extremely simple and highly efficient door-operating and holding mechanism intended for general use but especially well adapted for use in connection with horizontal swinging garage doors.

Generally stated, the invention consists of the novel devices and combinations of devices hereinafter described and defined in the 10 claims.

In the accompanying drawings, which illustrate the invention, like characters indicate like parts throughout the several views.

Referring to the drawings:

15 Fig. 1 is a plan view showing the invention applied to a pair of swinging doors and a door frame, some parts being broken away;

Fig. 2 is a fragmentary perspective view 20 of certain parts shown in Fig. 1;

Fig. 3 is a view partly in elevation and partly in section taken on the line 3—3 of Fig. 1 showing the door closed;

Fig. 4 is a view in elevation showing the 25 latch hook and closely associated parts;

Fig. 5 is a fragmentary detail view partly in elevation and partly in section taken on the line 5—5 of Fig. 1;

30 Fig. 6 is a fragmentary plan view of one of the toggle levers showing the pivotal connection between the arms thereof; and

Fig. 7 is an elevation of the same.

The numeral 8 indicates a door frame to which is hinged a pair of horizontal swinging doors 9 and 10.

The invention includes a pair of horizontal toggle levers 11 and 12 formed from commercial angle bars and arranged to swing just under the top member of the door frame 40 8 so as not to interfere with the head room of the door opening. The toggle lever 11 is relatively short, and one arm thereof is pivotally anchored to a bearing 13 secured to the top member of the door frame 8, and 45 the other arm thereof is pivotally anchored to the horizontal member of an angle bearing 14 on the inner face of the door 9. Formed with the toggle arm pivotally anchored to the bearing 14 is an extension 15, the edge thereof facing the door 9 being oblique and when said door is 50 open extends substantially parallel to the inner face of said door.

The toggle lever 12 is relatively long, and 55 one arm thereof is pivotally anchored to a V-shaped bearing 16 on the top member of the door frame 8, and the other arm thereof

is pivoted to a bearing 17 on the inner face of the door 10. Both toggle levers 11 and 12 have the horizontal flanges of their arms connected by bottom plates 18 to which the toggle arms attached to the doors 9 and 10 are rigidly secured and to which the toggle arms attached to the door frame 8 are pivoted at 19.

It is important to note that the ends of the arms of the toggle levers abut and stop the straightening movement thereof when slightly beyond dead centers and thereby hold the doors 9 and 10 fastened open. Said toggle levers 11 and 12 are arranged to 65 buckle by movements toward the hinged edges of the doors 9 and 10, respectively. The toggle arm flanges rigidly attached to the bottom plates 18 are beveled at 20 and the pivots 19 are off-center to permit the 70 arms of each toggle 11 and 12 to closely fold when the doors 9 and 10 are closed.

To start the initial buckling action of the toggle lever 11 and thereby permit the door 9 to be closed, there is provided a horizontal rod 21 turnably mounted in front and rear bearings 22 and 23, respectively, on the inner face of the door 9. Said rod 21, at its rear end portion is bent laterally upward to afford a cam-acting finger 24 which engages and extends transversely of the oblique inner edge of the toggle extension 15. The front end portion of the rod 21 is bent horizontally away from the inner face of the door 9 and then upward to afford a latch hook 25.

80 Encircling the rod 21 is a coiled spring 26 one end of which is anchored to the bearing 22 and the other end of which is secured to said rod. This spring 26 is under strain to turn the rod 21 and yieldingly hold the body 85 of the latch hook 25 against an overlying stop 27 on the bearing 22. On the top member of the door frame 8 is a latch plate 28 with which the latch hook 25 interlocks when the door 9 is closed. During the closing movement of the door 9, the latch hook 25 engages the latch plate 28 and is cammed thereby, against the tension of the spring 26, into a 90 position to pass under said plate and then spring into interlocking engagement therewith.

100 Mounted on the door 9 is a turnable handle 29 having on the inside of said door a crank arm 30 attached by a cable 31 to the body of the latch hook 25. By turning the handle 29, which is on the outside of the door 9, to turn the crank arm 30 downward, the 110

cable 31 draws the latch hook 25 downward against the tension of the spring 26 to release the same from the latch plate 28 and thereby permit the door 9 to be opened. When the handle 29 is released, the spring 26 returns the latch hook 25 to normal position and resets said handle and its crank arm 30 by means of the connection 31.

To close the door 9 it is first necessary to start the buckling movement of the toggle lever 11 and this is accomplished in the same manner as the releasing of the latch hook 25, towit: by operating the handle 29 to turn the rod 21 and thereby swing the cam finger 24 against the toggle lever extension 15 and move the same away from the door 9.

To automatically buckle the toggle lever 12 and close the door 10 by the closing movement of the door 9 a crosstie rod 32 has one of its ends pivoted to a bearing 33 on the inner face of the door 9 and its other end portion extended through a bearing 34 on the pivot 19 of its toggle lever 12 and is secured thereto in different longitudinal adjustments by a set screw 35. Preferably, the rod 32 is adjusted so that the door 10 closes just ahead of the door 9. When opening the door 9, the rod 32 straightens the toggle lever 12 and opens the door 10. By positioning the toggle levers 11 and 12 beyond dead centers when the doors 9 and 10 are open, they positively hold said doors open.

The above described invention, while extremely simple and of comparatively small cost to manufacture, has in actual usage proven highly efficient for the purpose had in view.

What I claim is:

1. The combination with a swinging door, of a toggle lever one arm of which is pivotally anchored and the other arm of which is pivoted to the door, said lever being arranged to move beyond a dead center at the completion of the opening movement of the door to fasten said door open, a turnable rod on the door and having a cam-acting member, and a connection for turning the rod to cause its cam-acting member to engage said toggle and buckle the same to permit the door to be closed.

2. The structure defined in claim 1 in which the rod is provided with a latch hook, a spring normally holding the rod with its cam-acting member inoperative and its latch hook operative, and a latch element with

which the latch hook engages to hold the door closed.

3. The combination with a swinging door, of a toggle lever one arm of which is pivotally anchored and the other arm of which is pivoted to the door, said lever being arranged to move beyond a dead center at the completion of the opening movement of the door to fasten said door open, a turnable rod having a cam-acting member and a laterally projecting latch hook, said member being arranged to engage the toggle lever and buckle the same to permit the door to be closed by a movement of the rod to release the latch hook, a spring normally holding the rod with its cam-acting member inoperative and its latch hook operative, and a connection for turning the rod to cause its member to buckle the toggle lever when the door is open and to release the latch hook when the door is closed.

4. The structure defined in claim 3 in which said connection is attached to the latch hook.

5. The combination with a swinging door, of a toggle lever one arm of which is pivotally anchored and the other arm of which is pivoted to the door, said lever being arranged to move beyond a dead center at the completion of the opening movement of the door to fasten said door open, said toggle lever having an extension outward of its connection with the door, a turnable rod on the door and having a cam-acting member, and a connection for turning the rod to cause its cam-acting member to engage the extension on the toggle lever to buckle said lever and permit the door to be closed.

6. The combination with a pair of swinging doors, of a pair of toggle levers having one of their arms pivotally anchored and their other arms pivoted one to each of said doors, said toggle levers being arranged to move beyond dead centers at the completion of the opening movement of the door to fasten the doors open, a manually operated connection for buckling one of the toggle levers to permit the respective door to be closed, and a connection actuated by the initial closing movement of said door to buckle the other of said toggle levers and close the door to which it is attached.

In testimony whereof I affix my signature.

MAURICE H. GRAHAM.
